[57] CLAIM

The ornamental design for a toy track way, as shown and described.

DESCRIPTION

FIG. 1 is a perspective view of a toy track way showing our new design;

FIG. 2 is a front elevational view thereof;

FIG. 3 is a cross-sectional view thereof taken along line 3—3 in FIG. 2;

FIG. 4 is a cross-sectional view of the track way shown on an enlarged scale; and

FIG. 5 is a side elevational view thereof shown on a reduced scale.
